UNITED STATES PATENT OFFICE.

WILLIAM F. HARBRECHT, OF SANDUSKY, AND FREDERICK BOERGER, OF DELPHOS, OHIO.

SUCTION-BOX.

No. 881,155

Specification of Letters Patent.

Patented Sept. 18, 1906.

Application filed January 23, 1905. Serial No. 242,457.

To all whom it may concern:

Be it known that we, WILLIAM F. HARBRECHT, of Sandusky, county of Erie, and FREDERICK BOERGER, of Delphos, county of Allen, State of Ohio, have invented certain new and useful Improvements in Suction-Boxes; and we do hereby declare that the following is a full, clear, and exact description of the invention, which will enable others skilled in the art to which it appertains to make and use the same, reference being had to the accompanying drawings, and to the figures of reference marked thereon, which form part of this specification.

15 This invention relates to new and useful improvements in the detail construction of suction-boxes for paper-making machines.

One object of the invention is to provide a suction-box of such simple design and construction that any mechanic possessing ordinary mechanical skill may place the same in position upon a paper-making machine.

Another object consists in arranging the cylinder which we employ with perforations of novel and peculiar form, whereby the surface of the felt subjected to suction is increased to a maximum.

A further object is to provide ready means for adjusting the suction-box relative to the perforated cylinder.

30 A further object is to provide conveniently-accessible means contained within the cylinder at its outer ends for revolvably mounting the same and for adjusting said means.

35 The invention comprises the various details of construction and the novel combination and arrangement of the parts herein-after fully described, and specifically defined in the appended claims.

40 The invention is illustrated in the accompanying drawings, which, with the characters of reference marked thereon, form part of this specification, like characters indicating like parts in the views.

45 In the drawings, Figure 1 is a side elevation showing our improved suction-box and showing the means for revolvably mounting the perforated cylinder. Fig. 2 is a vertical transverse section through the cylinder and 50 the suction-box, the plane of the section being indicated by the line $x-x$, Fig. 3. Fig. 3 is a sectional elevation of the cylinder and suction-box, the intermediate portion being broken away, the portion of the figure on the

right being in full lines, whereas the portion 55 on the left is in vertical section, indicated by the line $y-y$, Fig. 2. Fig. 4 is an enlarged sectional detail showing the form and arrangement of the perforations in the cylinder.

55 Referring to the drawings, 1 and 2, respectively, are end castings having the central obliquely-disposed bracket portions 3 and 4, extending on opposite sides, the outwardly-extending portions of the brackets being supported upon suitable standards 5, forming 60 part of the frame of the paper-making machine. The brackets 3 and 4 are hollow, whereby access to the interior is permitted.

65 6 represents rods connecting the end castings, being threaded at the ends and firmly 70 secured to the castings 1 and 2 by means of nuts 7 on opposite sides of the castings. Arranged preferably at equidistant points about the peripheries of the end castings are inwardly-extending rectangular-shaped recesses 8, the parallel sides of said recesses 75 serving as guides for sliding blocks 9, carrying rollers 10, adapted for revolvably mounting the perforated cylinder 11, which will be further described in detail.

80 12 represents adjusting-screws acting between the inner faces of the recesses 8 and the block 9 and providing means for adjusting the rollers 10 relative to the perforated cylinder. Extending into the castings 1 and 2 85 from the top margin to the plane top face of the brackets 3 and 4 are recesses 13, having upwardly-diverging side faces 14 and parallel guiding-faces 15. Arranged with its ends 90 resting in the recesses 13 is an elongated suction-box 16, having a cross-sectional exterior configuration corresponding to the shape of the recesses. This suction-box is open at the top, there being a suitable packing 17 occupying a groove entirely surrounding said 95 open top, and at the ends of the box and engaging the bottom are adjusting-screws 18, threaded upwardly through the upper portions of the hollow brackets 3 and 4. It will thus be seen that by reaching into the brackets 100 the suction-box may be readily adjusted in a vertical direction, being guided between the parallel faces 15 of the recesses 13.

105 19 indicates a pipe which connects with one end of the suction-box, the same connecting with a suitable exhaust device, such as a vacuum-pump. The cylinder is revolvably mounted upon the rollers 10, so as to op-

- erate in sliding contact with the suction-box, rotation being imparted thereto by the felt 20, operating over the same, although it is apparent that rotation of the cylinder independent of the action of the felt may be effected by any suitable mechanical means, such as a chain and sprocket connecting with a suitable part of the paper-making machine. Cylinder 11 is provided with closely-arranged 10 perforations 22. These perforations, as plainly shown in enlarged detail in Fig. 4, are cone-shaped, the openings on the inner face of the cylinder being small, whereas those on the outer face are large, and said perforations 15 are further arranged in intersecting diagonal rows, as indicated by the lines *a a* and *b b*. This arrangement of perforations provides a maximum of suction area with a minimum surface in actual contact with the felt. It is 20 apparent that by forming the cylinder with conical perforations, diverging from within outward a far greater suction area is provided than if these perforations were of uniform diameter throughout. Furthermore, if the 25 perforations were of uniform diameter and arranged as closely as indicated in the drawings the cylinder-walls would be obviously weakened. A cylinder constructed with conical perforations, as shown, will be exceedingly 30 strong, the tendency to buckle or spring while in operation being entirely eliminated. In order to prevent endwise movement of the cylinder 11 while in operation, there are provided flanges 23 at the outer margins of the 35 castings 1 and 2.
- It will be seen from the foregoing description that the parts of the invention are easily assembled and that the perforated cylinder and the suction-box are readily adjusted with 40 relation to each. The novelty, utility, and improved operation of the invention are apparent.
- Having described our invention, what we claim, and desire to secure by Letters Patent, 45 is—
1. A perforated rotating cylinder; combined with fixed end castings having flanges at their margins against which the ends of
- the cylinder abut, radially-disposed rollers within the castings for supporting the cylinder, and a suction-box.
2. A perforated rotating cylinder; combined with fixed end castings, each having an obliquely-disposed hollow bracket, screws threaded upwardly through the upper portions of said brackets, and a suction-box within the cylinder and adjustably supported on said screws.
3. A perforated rotating cylinder having open ends; combined with fixed end castings each of which has at its top a recess having a flat bottom, parallel guiding-faces, and above the latter diverging side faces, a suction-box of an exterior configuration corresponding to the shape of the recesses within which its extremities rest, and means for adjusting the box vertically therein.
4. A perforated rotating cylinder having open ends; combined with fixed end castings each of which has at its top a recess having a flat bottom, parallel guiding-faces, and above the latter diverging side faces, a suction-box of an exterior configuration corresponding to the shape of the recesses within which its extremities rest, hollow brackets on the end castings, and screws threaded upwardly through said brackets against the bottom of the suction-box, for the purpose set forth.
5. A rotating hollow cylinder, and a stationary suction-box therein; combined with fixed castings at the ends of the cylinder, means on the castings for adjustably supporting the box, said castings having rectangular radially-disposed recesses, a block in each recess carrying a roller contacting with the inner face of the cylinder, and an adjusting-screw between the inner side of the block and the inner wall of the recess.

In testimony that we claim the foregoing as our own we affix our signatures in presence of two witnesses.

WILLIAM F. HARBRECHT.
FREDERICK BOERGER.
